EXTRUDED FROZEN POTATO PRODUCT

Jerry L. Sloan, Portland, Oreg., assignor to Amfac Foods, Inc., doing business as Lamb-Weston, Portland, Oreg.

Filed Apr. 24, 1975, Ser. No. 571,360

Term of patent 14 years

Int. Cl. D1—01

U.S. Cl. D1—2

FIG. 1 is a side perspective view of an extruded frozen potato product showing my new design;

FIG. 2 is a front view thereof;

FIG. 3 is a back view thereof;

FIG. 4 is a plan view thereof;

FIG. 5 is a sectional view taken on line 5—5 of FIG. 1; and

FIG. 6 is a sectional view taken on line 6—6 of FIG. 1.

I claim:

The ornamental design for an extruded frozen potato product, as shown.
